GRINDING MILL.
APPLICATION FILED SEPT. 13, 1913.

Patented July 13, 1915.
2 SHEETS—SHEET 2.

The drawing shows a vertical pipe assembly. At the top, a flange is secured to the pipe with bolts labeled 8^c. A valve component, labeled 3^w, 3^u, and 3, is attached to the pipe. The pipe itself is labeled with various parts: 8^a, 8^b, 8^c, 7, 8⁵, 8^c, 7^a, 8^b, 8^c, 7^g^a, 8^b, 3^w, 3^u, and 3. A separate detail drawing, labeled 'Fig. 5.', shows a cross-section of the valve assembly, featuring a central stem and a seat with a gasket.

UNITED STATES PATENT OFFICE.

SIMON SNYDER, OF MUNCY, PENNSYLVANIA, ASSIGNOR TO SPROUT, WALDRON & COMPANY, OF MUNCY, PENNSYLVANIA, A CORPORATION OF PENNSYLVANIA.

GRINDING-MILL.

1,146,030.

Specification of Letters Patent. Patented July 13, 1915.

Application filed September 13, 1913. Serial No. 789,699.

To all whom it may concern:

Be it known that I, SIMON SNYDER, a citizen of the United States, residing at Muncy, in the county of Lycoming and State 5 of Pennsylvania, have invented certain new and useful Improvements in Grinding-Mills; and I hereby declare that the following is a full, clear, and exact description thereof, reference being had to the accompanying drawings, which form part of this specification.

This invention is a novel improvement in grinding mills, of that class commonly called attrition mills, in which the grinding 15 is effected by means of two opposed circular disks mounted face to face on independent axially aligned shafts rotating in opposite directions.

The objects of the present invention are: 20 First, to so construct the base of the mill that the shafts of the disks may be kept in absolutely accurate alinement, and for this purpose the base frame of the machine is cast with integral standards which rise approximately to the axial line of the shafts, and on which the journal boxes for the 25 shafts are directly secured, doing away with any adjustable or detachable standards on the base for supporting the journal boxes 30 and greatly simplifying and economizing the construction while enhancing the durability and efficiency of the machine.

Second, to have one of the disk carrying 35 shafts and its journal boxes bodily adjusted longitudinally of the shaft to enable the disks to be separated axially, so that the grinding surfaces of the disks may be repaired when necessary without having to dismount the disks from their shafts or the 40 shafts from their bearings, and without disturbing the adjustment of the grinding regulating devices. In this construction the devices for regulating the grinding adjustment of the disks are movable with the 45 bearings and the adjustment of such devices does not have to be disturbed by the said separating movement of the disks.

Third, to provide a novel sealing ring to 50 seal the grinding case around the feed opening and shaft so that material cannot pass through the grinding case without being subjected to the grinding action of the disks.

I will explain the invention more in detail 55 with reference to the accompanying draw-

ings which show one practical embodiment of the invention, and refer to the claims for concise summaries of the invention and features thereof for which I desire protection.

In said drawings—Figure 1 is a side elevation of the mill. Fig. 2 is a top plan view of the base frame detached. Fig. 3 is an enlarged detail longitudinal vertical section through part of the mill showing the means for bodily adjusting the bearings of one of the shafts, with the shaft and grinding disk thereon, longitudinally of the base; and also showing such parts in working position in full lines; and in retracted position in dotted lines. Fig. 4 is a transverse section on line 4—4, Fig. 3, showing the sealing ring. Fig. 5 is an enlarged detail section on line 5—5, Fig. 4. Fig. 6 is a detail section on line 6—6, Fig. 3.

The base of the mill is preferably rectangular in form and is composed of a base frame 1 from which rise four integral transversely disposed standards 1^a, 1^b, 1^c, 1^d, which are substantially alike, except standards 1^c, 1^d are preferably longer, longitudinally of the base, than the other standards. Intermediate the standards 1^c, 1^d is an opening 1^f, and intermediate the standards 1^a, 1^b, is an opening 1^g; which opening might be covered if desired.

Intermediate and connecting the standards 1^b, 1^c is an integral bowl-like portion 1^e which forms the lower half of the grinding case or housing, and which has a hopper-shaped bottom 1^h by which the ground material may be discharged from the grinding case.

The standards 1^a, 1^b, 1^c, 1^d rise to approximately the axial line of the main shafts 2 and 3 which are journaled in bearings on said standards. The left hand shaft 2 carries the grinding disk 2^r on its inner end and is journaled in boxes 2^b, 2^c mounted on the upper end of the standards 1^a, 1^b. The right hand shaft 3 carries the grinding disk 3^r on its inner end, and is journaled in boxes 3^b, 3^c respectively mounted on the standards 1^c, 1^d.

Preferably as shown in Fig. 6 the journal boxes 2^b, 2^c, 3^b, 3^c are polygonally shaped on their lower sides, in cross section and fitted in correspondingly shaped longitudinal recesses in the upper ends of their respective standards, so that when the bearings are in

place on said standards they are held firmly against lateral displacement.

The bearings 2^b, 2^c may be secured in place on their respective standards by means of bolts 2^l, 2^l tapped through lateral ears on the boxes and engaging threaded apertures in lateral projections 1^b, 1^l on the sides of the standards 1^a, 1^b, as shown. The boxes 3^b, 3^c are similarly fitted on the standards 1^c, 1^a and may be secured when the disks are in operative position by means of bolts 3^k, 3^l tapped into threaded openings in lateral projections 1^k, 1^l on the standards 1^c, 1^a.

15 As shown the shafts 2 and 3 are preferably mounted in ball bearings in their respective journal boxes as indicated in the drawings, such ball bearings however form no part of the present invention and may be 20 of any suitable construction.

25 The disks 2^r, 3^r are inclosed within a grinding case or housing, the lower part of which is formed by the part 1^e of the base as above described, and the upper part of 30 which is formed by a shell or casing 4, the lower part of which corresponds in contour to the upper end of the part 1^e of the base, and the casing 4 is fitted on this part 1^e; said parts have meeting flanges 4^m, 1^m, and may be fixedly secured together by bolts transfixing said flanges, or in any other desired manner.

35 The casing 4 has a chute or fixed spout 4^a at one side which discharges through an opening 4^b in the wall of the case around the inner end of shaft 2, and the hub of the grinding disk 2^r is provided with radial openings or eyes 2^w for the passage of the grain as usual. The particular construction 40 of the grinding disks 2^r, 3^r is not a feature of the present invention; any suitable kind may be employed, but that on shaft 2 should have an eye or eyes for the passage of the grain from the spout 4^a to and between the 45 disks. The spout 4^a may receive the grain from a hopper 4^e of any suitable construction mounted on the casing 4, and provided with any suitable feeding devices.

50 The shafts 2 and 3 may be rotated in opposite directions by any suitable means, and are shown as provided with pulleys 2^p, 3^p which may be belted to drivers, not shown.

55 The journal box 3^b is preferably formed with a plate 3^m on its inner end which is adapted to fit in and close a corresponding opening 4^c in the adjacent side of the grinding case, which opening is provided to permit the hub of the disk 3^r to project through the side wall of the housing when the grinding disk 3^r is separated from the disk 2^r, as hereinafter described, to renew or repair the grinding faces of the disks. When the disks are in normal working position the plate 3^m tightly closes said opening.

65 The journal boxes 3^b and 3^c are both

slidable longitudinally on their standards 1^c, 1^a, and the box 3^b is preferably provided on its under side with a rack, as 3^a which is adapted to engage a pinion 5^a on a counter-shaft 5 journaled in suitable bearings in the standard 1^c. The outer end of this shaft 5 may be squared, as at 5^a, for the engagement of a crank or wrench by which said shaft can be turned when it is desired to shift the box 3^b; but before this box can be moved it is necessary that the bolts 3^k, 3^l be removed. When these bolts are removed by rotating shaft 5 the box 3^b can be moved longitudinally and with it the box 3^c, shaft 3, runner 3^r and pulley 3^p, are all moved longitudinally of the base to the position indicated in dotted lines in Fig. 3.

In order to cause the shaft 3 to move longitudinally with the box 3^b the ball bearing 3^u on which this shaft is mounted in box 3^b is rigidly confined against longitudinal movement relative to the shaft between a sleeve 3^v (strung on the shaft between the hub of disk 3^r and the bearing 3^u) and a nut or collar 3^w on the opposite side of the bearing 3^u. The shaft 3 is rotatably but normally longitudinally immovably mounted in box 3^c by having the ball bearing 13 on which it is mounted in said box confined between a collar 13^a and a disk 13^b in the box. The collar 13^a is normally forced outward by a spring 13^c, and disk 13^b forms part of the end thrust bearings for shaft 3. The construction is such that when the box 3^b is moved longitudinally it will move shaft 3, box 3^c, and all the connected parts, longitudinally of the base with it.

In the box 3^c are mounted end thrust bearings 3^x for the shaft 3, and devices 3^y for adjusting the grinding position of this shaft, but such adjusting devices are not claimed herein and are simply illustrated to show that the separation of the grinding disks, as indicated in dotted lines in Fig. 3, does not disturb the adjustment of the grinding regulating devices, and when the shaft and parts are returned to the position shown in full lines in Fig. 3, and the boxes 3^b, 3^c fastened in place by bolts 3^k, 3^l, the machine is again ready for operation.

When the parts are retracted to the position shown in dotted lines in Fig. 3 the grinding faces of the disks 2^r, 3^r can be inspected and the grinding surfaces 2^t, 3^t thereof can be removed and replaced through openings in the housing, which openings are normally closed by suitable plates 4^t when the mill is in operation. Thus whenever it is desired to repair, remove, or renew the grinding surfaces 2^t it is not necessary that the mill be dismantled; and this saves time and labor in the maintenance of such mill.

It is important in the practical operation of these machines that all the grain fed from the hopper be compelled to pass through the

eyes 2^w of the grinding disk 2 in order that it shall pass between the grinding surfaces 2^t, 3^t, whereby it is reduced before it can escape into the housing. In order to make 5 a close joint between the said disk 2^r and the opening 4^b, in the wall of the housing communicating with the spout 4^a, I preferably attach to the outer end of the hub of disk 2^r a ring 6 having an annular flange 6^a 10 that projects into the opening 4^b; and to the wall of the housing adjacent this ring 6, and surrounding opening 4^b, I attach a sealing ring which is composed of preferably four or more segmental sections 7, the ends of 15 which overlap as shown at 7^a so as to permit expansion or contraction of the ring by radially adjusting said sections. These sections surround the flange 6^a and are adjustable so as to be closely fitted to the exterior 20 face of said flange. To support the sealing ring adjustably in the casing and around the ring 6, I preferably provide each ring section with two or more openings 7^b which are engaged by studs 8^b projecting eccentrically from the ends of bolts 8, through 25 openings in the adjacent wall of the housing, which bolts are provided with jam-nuts 8^c by which they can be locked when adjusted. By turning bolts 8 the ring sections 30 7 can be moved radially, in or out, by reason of the engagement of openings 7^b with eccentric studs 8^b, and when properly adjusted can be fastened in position by tightening the jam-nuts 8^c. The sections can be clamped. 35 tightly against the wall of the housing by means of nuts 8^a on the ends of the studs 8^b, which are threaded for engagement of these nuts, see Fig. 5. By this means a close adjustable seal is made between the runner or 40 disk 2^r and the wall of the housing or grinding chamber, and leakage of grain past the grinding disks is prevented.

What I claim is:

1. In a grinding mill the combination of 45 oppositely disposed grinding disks, a housing in which said disks are mounted, a feed spout for supplying feed to said disks communicating with said housing through an opening adjacent the eye of one of the disks, 50 an annular flange on said disk adjacent said opening, a sectional sealing ring surrounding said flange, eccentric bolts engaging openings in said sections for adjusting them, and means for clamping the sections when 55 adjusted.

2. In a grinding mill the combination of 60 oppositely disposed disks, a housing in which said disks are mounted, a feed spout for supplying feed to said disks communicating with said housing through an opening adjacent the eye of one of the disks; an annular flange on said disk adjacent said opening, a sectional sealing ring surrounding said flange, stud bolts through the walls 65 of the housing and having eccentrically lo-

cated pins on their inner ends engaging slots in the sealing ring sections for adjusting the latter closely around the annular flange, and means for clamping the sealing ring sections when adjusted.

3. In a grinding mill the combination of a 70 housing, a grinding disk therein, a feed spout communicating with said housing through an opening adjacent the hub of said disk, a sectional sealing ring surrounding said opening, means for clamping said ring sections and eccentric devices for adjusting said sections around said opening.

4. In a grinding mill the combination of 75 a bearing, a grinding disk therein, a feed spout communicating with said housing through an opening adjacent the disk, an annular flange on said disk adjacent said opening, a sectional sealing ring surrounding said flange, and eccentrically adjustable 80 pins engaging the sealing ring sections for adjusting the latter closely around the said flange.

5. In a grinding mill, the combination 85 with a base frame, longitudinally disposed shafts mounted thereon and opposed grinding disks on the inner adjacent ends of said shafts, one of said shafts being movable longitudinally with its bearings, and a set of independently adjustable housings for said 90 bearings simultaneously slidably with the shaft longitudinally of the base to permit said shaft and its disk to be moved longitudinally of the frame to bodily separate the 95 disks.

6. The combination in an attrition mill of 100 a base frame having standards thereon, journal boxes or housings mounted on said standards, bearings in said boxes, and axially aligned runner-shafts journaled in said bearings; the boxes containing the bearings for one of said shafts being slidably mounted on adjacent standards, and means for moving said slidable boxes bodily with the shaft to 105 separate the runner-heads.

7. In an attrition mill, the combination of 110 a base frame, standards on said frame, journal boxes or housings mounted on said standards, bearings in said boxes, and axially aligned runner-shafts journaled in said bearings; one of said shafts being movable endwise with its bearings and the boxes containing the movable shaft bearings being slidably mounted on adjacent standards, together with means for moving said slidable 115 boxes bodily with the shaft journaled therein without changing the position of the bearings relatively to the boxes in which they are contained.

8. In a grinding mill, a base frame having 120 standards thereon, axially aligned runner-shafts mounted on said standards, one of said shafts being journaled in bearings movable longitudinally with the shaft, housings for said bearings slidably mounted on adja- 125

cent standards, and means for moving said housings bodily with the shaft to separate the runner-heads.

9. In an attrition mill, a base frame having standards thereon, journal boxes or housings slidably mounted on said standards, bearings in said boxes, axially alined runner-shafts journaled in said bearings; one shaft being adjustable endwise with its bearings and the boxes in which the latter shaft is journaled being movable longitudinally with the shaft, a rack on one of said movable boxes, and a shaft geared to said rack, whereby the movable boxes may be shifted bodily with the shaft to separate the runner-heads without disturbing the grinding adjustment of said shaft in its bearings.

10. In a grinding mill the combination of a base, a housing, a pair of axially alined shafts mounted in bearings at opposite sides of the housing and extending into the housing, grinding disks on the ends of said shafts within the housing, the inner bearings for one of said shafts being slidably mounted and the shaft being rotatably but normally longitudinally immovably journaled in said bearing, said housing having an opening in its side next said bearing to permit the projection of the adjacent disk hub therethrough, and a cover for said opening attached to and movable with the said slidable bearing and adapted to close said opening when the parts are in grinding position, and to inclose the housing when the bearing and shaft are moved outwardly.

11. In a grinding mill the combination of a base, a housing, a pair of axially alined shafts mounted on said base at opposite sides of the housing and extending into the housing, and grinding disks on the ends of said shafts within the housing, an inner bearing for one of said shafts slidably mounted on the base, and said housing having an opening in its side next the said slidabile bearing to permit the projection of the adjacent disk hub therethrough when the

shaft and bearing are moved outward, and a cover for said opening attached to and movable with the said slidable bearing and adapted to close said opening when the parts are in grinding position.

12. In a grinding mill the combination of a base, a housing, axially alined shafts mounted on the base and extending into the housing, grinding disks on said shafts within the housing, slidable bearings for one of said shafts, said housing having an opening in its side next the adjacent slidable bearing to permit the projection of the disk hub therethrough, and a cover for said opening attached to and movable with said adjacent slidable bearing adapted to close said opening when the parts are in grinding position.

13. In a grinding mill the combination of a housing, oppositely disposed grinding disks therein, a feed spout communicating with said grinding disks through an opening in the housing adjacent the eye of one of the disks, a sectional sealing ring surrounding said opening, means for clamping the sealing ring sections in position around said opening, and eccentric devices for adjusting the ring sections to contract or expand the ring, substantially as described.

14. In a grinding mill the combination of a housing, opposite grinding disks therein, a spout communicating with said disks through an opening in the housing adjacent the eye of one of the disks, an annular flange on the latter disk adjacent said opening, a sectional sealing ring surrounding said flange, eccentric devices for adjusting said sections to expand or contract the ring, and means for clamping the ring sections when adjusted.

In testimony that I claim the foregoing as my own, I affix my signature in presence of two witnesses.

SIMON SNYDER.
